UNITED STATES PATENT OFFICE.

THOMAS HARRIS, OF RAVENSWOOD, NEW YORK.

HAND-TRUCK.

1,367,316.

Specification of Letters Patent.

Patented Feb. 1, 1921.

Application filed December 19, 1919. Serial No. 345,947.

To all whom it may concern:

Be it known that I, THOMAS HARRIS, a citizen of the United States, and residing at Ravenswood, L. I., in the county of 5 Queens and State of New York, have invented certain new and useful Improvements in Hand-Trucks, of which the following is a specification, such as will enable those skilled in the art to which it appertains to make and use the same.

This invention relates to hand trucks, and the object of the invention is to provide a simple, cheap, and durable hand truck, and one which is so constructed that it may be 15 conveniently used for handling boxes, barrels and like objects, or articles in moving the same from place to place; a further object being to provide a removable foot piece which forms a support for articles placed 20 on the truck; and with these and other objects in view the invention consists in the improved construction and arrangements of parts as hereinafter described and claimed.

The invention is fully disclosed in the 25 following specification, of which the accompanying drawing forms a part, in which the separate parts of my improvement are designated by suitable reference characters in each of the views, and in which:

30 Figure 1 is a perspective view of the improved truck;

Fig. 2 a similar view with the foot removed;

Fig. 3 a perspective view of the foot;

35 Fig. 4 a longitudinal sectional view; and,

Fig. 5 a bottom plan view of the lower end portion of the truck.

Referring to the drawings A is the body portion, B the axle, C the wheels and D the 40 handle of the truck. To the under side of the body portion A are secured the spaced cross bars E, and between which the axle B is arranged. The cross bars E are connected by the plates F, F', and upon the 45 plates F, blocks f are secured for holding the axle into firm engagement with the under side of the body portion. The plate F' is extended to the front of the body portion and is then bent at right angles to extend upward above the top of the body portion, as at f' to form a brace for a purpose 50 hereinafter described.

The under side of the body portion is provided with a longitudinal recess in which 55 the handle D, is secured by bolts d, and to

the rear end of the body portion at each corner thereof is secured a leg G. The handle is provided at its ends with a cross bar d² to form hand pieces. The handle is also provided with openings d'.

60 The forward end of the body portion is provided with a removable foot piece H. This foot piece consists of a bar h, provided on its front face with a plate h', which is of a width greater than that of the bar h 65 so as to project above the same as clearly shown in the drawings. The bar h is provided with pins h² on its under face to enter the openings a in the body portion A and also to enter the openings d' in the handle 70 D when the foot piece H is not in use. The rear face of the bar h is recessed and extending across said recess is a plate h³, which plate with the recess forms a keeper or loop 75 to receive the upwardly projecting end f' of the plate F'.

To the upper face of the body portion at its rear end is secured a cross bar or cleat I, which is of a length equal to the width of the body portion, and at the sides near 80 the middle of the length of the body, cleats J are secured. These cleats with the foot piece serve as means for holding a box or barrel on the truck.

To prevent boxes and the like placed on 85 the truck from coming in contact with the wheels, guards K are employed. These guards consist of angular plates secured upon the upper face of the body and each having a member thereof projecting over 90 the wheels as shown.

By the above described construction, a 95 cheap, strong and durable truck is produced and one upon which articles can be readily placed and removed.

It will be understood that the foot piece H will be preferably used when boxes, crates and the like are supported on the truck, and this foot piece is preferably removed and the projecting end f' of the plate F' is used 100 when barrels and similar objects are supported on the truck, and while I have shown certain details of construction for carrying my invention into effect, it will be understood that various changes in and modifications of these details of construction may be made, within the scope of the appended 105 claim, without departing from the spirit of my invention or sacrificing its advantages.

Having fully described my invention, 110

what I claim as new and desire to secure by Letters Patent, is;—

A hand truck of the class described comprising an oblong rectangular body portion, 5 a handle member at one end of the body portion, the back of said body portion being provided adjacent to the lower end thereof with two transversely arranged and spaced strips, an axle mounted between and reinforced by said strips the ends of said axle extending beyond the sides of the body portion, 10 wheels mounted on the protruding ends of said axle, and other strips secured

to said transversely arranged strips for holding said axle against displacement and one 15 of said strips extending outwardly and upwardly over the lower end of said body portion to form a footpiece therefor.

In testimony that I claim the foregoing as my invention I have signed my name in 20 presence of the subscribing witnesses this 15th day of December, 1919.

THOMAS HARRIS.
